UNITED STATES PATENT OFFICE

2,137,379

FILM ENVELOPE

Noel Pemberton Billing and Ambrose Henry Tapper, London, England; said Tapper assignor to said Billing

Application August 4, 1937, Serial No. 157,440
In Great Britain August 13, 1936

5 Claims. (Cl. 95—66)

This invention consists in improvements in or relating to photographic film packages of the type comprising inner and outer envelopes, the outer one of which is formed with a mask through which the film or other light-sensitive material may be exposed when the envelopes are separated apart, as for instance in a construction somewhat similar to that described in prior United States Letters Patent Nos. 2,017,709 and 10 2,070,778 of Noel Pemberton Billing, dated October 15, 1935, and February 16, 1937, respectively.

The present invention comprises in combination inner and outer envelopes of the type referred to, a flexible tongue on one of them and a loop on the other through which the tongue will slide as the envelopes are moved relatively to one another as for example when they are separated for the purpose of exposure. Preferably the tongue is formed from or is provided on the outer surface of what may be regarded as the back of the outer envelope and the loop is on the inner envelope.

In describing the invention the upper edge of the outer envelope will be considered as that edge or margin at the opening of the envelope through which the inner envelope is entered and this edge will generally be uppermost in the use of the package in a camera. The "lower edge" 30 of the inner envelope will be considered as that edge which is remote from the "upper edge" of the outer envelope when the two are closed one into the other.

In order that the invention may be more clearly understood a preferred construction will now be described with the aid of the accompanying drawing, in which—

Figure 1 illustrates the blank from which the outer envelope is formed, and

Figures 2 to 5 illustrate successive steps in the assemblage of the package, Figure 5 being a section on the line 5—5 of Figure 4.

Like reference numerals indicate like parts throughout the several figures of the drawing.

In the example illustrated in Figures 1 to 5 the inner envelope is a plain envelope open only at its lower end with an aperture 50 formed in the material of what may be considered as the rear wall of the envelope, that is that wall remote from the masked opening in the outer envelope to be described below. The inner envelope otherwise may be formed in any other preferred manner and adhesive or overlapping and interlocking flaps may be employed to complete the

folding and closure of the inner envelope in a manner well known and well understood.

The outer envelope comprises four panels 24, 25, 26 and 27, and in panel 25 an aperture 28 is provided to constitute a mask through which the surface of a sensitized sheet of material 29 will be exposed when the inner envelope is withdrawn.

At the lower edge of the mask a flap 35 is provided which is folded over along the fold-line 10 37 to afford a means for effecting a light-seal along the lower margin of the opening.

Each of the side panels 24 and 26 is slotted at 51 to provide tongues 52 at the outer margins of the panels.

In assembling the package the light-sensitive material 29 is placed on the flap 27 with the sensitized surface uppermost and is held at one edge in fold 34 along which the panel 27 is subsequently folded to overlie panel 25. At its opposite edge the material 29 is retained by an overturned tongue portion 53 cut from the material of panel 27. This tongue portion does not extend the full width of the panel but is located in the central portion thereof. After placing the material 29 in position in the manner just described the inner envelope is passed over the panel to enclose the light-sensitive material and the panel together with the inner envelope is then folded over panel 25 along line 34.

Panels 24 and 26 are next folded over panel 27 and in so doing tongues 52 are both inserted through slot 50 in the rear wall of the inner envelope. Extension flaps 54 projecting from the lower edges of the inner portions of panels 24 and 26 are brought over the front edge of the envelope and are secured thereto by adhesive or in any other preferred manner. For example, an adhesive label may be pasted over the rear flaps 24 and 26 after assemblage to hold the parts of the panel firmly in place and if desired a portion of the label can extend to the upper edge of the inner envelope to be removed therefrom prior to the separation of the envelopes for exposure.

In the construction of Figures 1 to 5 the upper extremities of slots 51 serve to limit the degree of withdrawal of the inner envelope 20 and to prevent its complete withdrawal from the outer envelope, and the permissible degree of separation can therefore be determined by the position of the upper ends of slots 51.

It must be realized that Figure 5 indicates a sectional view in a somewhat schematic manner with all the various layers of the package sep-

arated apart in order to show them clearly. In practice, however, the package will be very thin and successive layers will be more or less in rubbing contact flat against one another. In the construction described the inner envelope forms a complete enclosure for the light-sensitive material 29 when the package is closed and consequently pressure on opposite lateral edges of the package, such as would tend to bulge the margins of the masked opening 28, will have no ill effect on the material 29 owing to its complete enclosure in the inner envelope.

We claim:

1. A photographic package comprising relatively slidable inner and outer envelopes each having an open end and whereof the inner envelope serves to enclose the light sensitive material and the outer envelope has one wall formed as a mask through which the light sensitive material is exposed when the inner envelope is slidably withdrawn from the outer envelope, and comprising a tongue carried by the outer surface of what may be regarded as the back of the outer

envelope, and a loop on the inner envelope through which the tongue will slide as the envelopes are moved relatively to one another as during separation for the purpose of exposure, which tongue and loop serve to limit said movement of separation. 5

2. A photographic package according to claim 1 in which the flexible tongue is formed integrally with the outer surface of what may be regarded as the back of the outer envelope. 10

3. A photographic package according to claim 1 in which the flexible tongue is formed integrally with to form part of the outer surface of what may be regarded as the back of the outer envelope. 15

4. A photographic package according to claim 1 in which the tongue is wholly outside the envelope.

5. A photographic package according to claim 1 in which all the parts of both envelopes are 20 formed of thin sheet material by folding.

NOEL PEMBERTON BILLING.
AMBROSE HENRY TAPPER.
